(57) **CLAIM**

I claim the ornamental design for a windshield cleaner, as shown and described.

DESCRIPTION

FIG. 1 is a bottom, front and right side perspective view of a windshield cleaner, showing my new design;

FIG. 2 is a shrinkage state view thereof;

FIG. 3 is a top, rear and right side perspective view thereof;

FIG. 4 is a front side elevational view thereof;

FIG. 5 is a rear side elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines shown in the drawings illustrate portions of the windshield cleaner that form no part of the claimed design.

1 Claim, 9 Drawing Sheets
